MACHINE FOR OPERATING UPON SHEET MATERIAL

Homer F. Smith, Chicago, Ill., assignor to United Shoe Machinery Corporation, Paterson, N. J., a corporation of New Jersey

Application April 3, 1934, Serial No. 718,863

19 Claims. (Cl. 12—52)

The present invention relates to machines for operating upon sheet material and is herein illustrated as embodied in a machine for forming and assembling moccasin upper parts, said machine, as illustrated, being especially adapted for forming and assembling the forepart member or vamp of an imitation moccasin upper and the toe piece or "plug" of such an upper preparatory to uniting these parts permanently, for example, by a 10 sewn seam.

10 In assembling the toe piece and the vamp of a moccasin upper it has been a usual practice to form a toe piece engaging flange on the marginal portion of the vamp adjacent to its concave edge, to form a vamp engaging flange on the marginal portion of the toe piece adjacent to its convex edge, to apply cement to the surfaces of said flanged portions which are to be brought into juxtaposition and then to assemble by hand the toe piece and the vamp and to press said flanged portions together by hand in order to cause the cement to secure them together temporarily until they are permanently united, for example, by a sewn seam.

25 Objects of the present invention are to provide a machine for use in the preparation of moccasin uppers for the usual shoe bottoming operations and, more particularly, to provide a machine for use in carrying out the procedure 30 above outlined. Advantages secured by the use of such machines include increased uniformity and improved quality of the work and substantial increase in production by relieving the operator of the slow and tedious hand operations 35 involved in assembling the vamp and the toe piece and pressing their flanged portions together by hand.

A feature of the invention contemplates the provision, in a machine for operating upon sheet 40 material, of a work support, a flange former comprising a plate movable perpendicularly relatively to the work support, said plate having a flange forming edge face arranged in parallel relation to a flange forming edge face of the 45 work support and constructed and arranged to cooperate with the flange forming edge face of said support to form a flange between said edge faces, and a work gage carried by the flange former and having its work gaging edge face arranged in parallel relation to said edge faces of the flange former and the work support, said gage operating to measure a uniform width of 50 the marginal portion of the work when the appropriate edge of the work is brought into contact 55 with the gage.

In the application of the invention to the preparation of moccasin upper parts for assembly, another feature thereof contemplates the provision, in a machine for operating upon the toe piece and the vamp of a moccasin upper, of 5 a support for the toe piece, a support for the vamp, a flange former movable relatively to said supports, said flange former comprising a head provided with a flange forming plate constructed and arranged to operate on the vamp and provided 10 with another flange forming plate constructed and arranged to operate on the tongue, and means for actuating said flange formers.

In the application of the invention to the assembly of the flanged toe piece and the flanged 15 vamp of a moccasin upper, a further feature of the invention contemplates the provision, in a machine for assembling the toe piece and the vamp of a moccasin upper, of a member constructed and arranged to support a vamp provided 20 with a marginal toe piece engaging flange and a member constructed and arranged to support a toe piece provided with a marginal vamp engaging flange, said supports being relatively movable to bring the toe piece and the vamp into assembled 25 relation and to press said flanged margins together.

These and other features of the invention, including certain details of construction and combinations of parts, will now be described with reference to the accompanying drawings and will be pointed out in the appended claims.

In the drawings,

Fig. 1 is a side elevation of a machine embodying the features of the present invention showing 35 a vamp and a toe piece positioned on the work supports and arranged in contact with the work gages;

Fig. 2 is a front elevation of the head of the machine illustrated in Fig. 1;

Fig. 3 is a plan view illustrating particularly the work supports and the flange formers;

Fig. 4 is a detail side elevation of the head of the machine showing the flange formers in operative relation to the work after the flanges have been formed;

Fig. 5 is a side elevation of the head of the machine showing the arrangement of the operating instrumentalities at the end of the cycle of operations and showing the shoe parts in assembled relation; and

Fig. 6 is a perspective view of an imitation moccasin upper which has been assembled upon the illustrated machine and stitched together part 55

way around the line of union of the vamp and the toe piece.

The present invention is illustrated in its application to the forming and assembling of certain parts of imitation moccasin uppers, namely, the vamp 88 (Fig. 6) and the toe piece 90. These parts, when united and then stitched to suitable quarters, form an upper which may be bottomed in any usual and convenient manner, for example, as a Goodyear welt shoe or as a shoe of the McKay type, the vamp 88 being of a sufficient width to provide the appropriate lasting allowance.

Referring to Fig. 1, the numeral 10 indicates the table of the machine frame upon which is mounted a support 12 for the vamp 88 and a support 14 for the toe piece 90 of an imitation moccasin upper. The concave edge face 16 of the vamp support has substantially the same contour as that portion of the margin of the vamp which is to be united to the tongue in order to form the complete forepart of the upper. Similarly, the toe piece support 14 is provided with a convex edge face 18 which has substantially the same outline as the margin of the toe piece which is to be united to the vamp. Cooperating with the vamp support 12, there is provided a flange former 20 and cooperating with the toe piece support 14 there is provided a flange former 22, said flange formers, as shown in Fig. 3, being integral parts of a horizontal plate which is made rigid by longitudinal ribs 24 and a transverse rib 26. The flange former 20 is provided with an edge face 21 having a contour which is the reverse of the contour of the edge face 16 of the vamp support 12. Said edge faces 16 and 21, when in operative relation, as seen in Figs. 3 and 4 are arranged in parallel relation to each other and spaced apart from each other a distance substantially equal to the thickness of the vamp in order to permit the formation of a flange between the vamp support and the flange former (Fig. 4). Similarly, the flange former 22 has a wall 23 which, as shown in Fig. 3, is parallel to the edge face 18 of the toe piece support and is spaced from said edge face a distance substantially equal to the thickness of the toe piece in order to permit the formation of a flange in the toe piece between said wall and said edge face. In order to afford a limited vertical movement of the flange formers relatively to the work supports, the flange former unit is provided with parallel, vertical shafts 28 which are secured within bosses 30 extending upwardly from the flange former unit and formed integrally with the transverse rib 26. The shafts 28 are mounted within bearings formed in bosses 32 extending downwardly from opposite sides of the table 10 and arranged to position the flange formers to register with the work supports (Fig. 3). The flange former unit is normally held retracted, as shown in Fig. 5, by two compression springs 34 coiled about the shafts 28, respectively, the upper end of each of said springs extending upwardly into the superimposed boss 30 on the flange former unit (Fig. 1), the shaft-receiving opening of which has its lower portion enlarged sufficiently to receive said springs. Similarly, the lower end of each of said springs extends downwardly into the table 10, the shaft-receiving opening of which is enlarged throughout a portion of its extent sufficiently to receive said springs. In order to gage the position of the vamp relatively to the work support and the flange former 20, a gage member or plate 40 is arranged to extend downwardly from the

under surface of the flange former 20, said gage member being provided with a work-gaging edge face 41, arranged in parallel relation to the edge face 21 of the flange former and spaced inwardly therefrom a distance equal to the width of the flange to be formed on the vamp. In order to centralize the toe piece transversely thereof upon the toe piece support 14 and also to position the toe piece lengthwise thereof upon its support in order that the margin of the toe piece projecting 10 beyond the edge face 18 of its support may be uniform, a gage member or plate 42 is secured to the under surface of the flange former 22 (Fig. 2) and provided with an edge face 44 (Fig. 3) for gaging the position of the toe piece upon its support. The edge face 44, when the gage 42 is in operative position, is spaced from the edge face 18 of the toe piece support a distance substantially equal to the width of the flange which is to be formed in the toe piece. The flange former unit is actuated by a treadle 46 (Fig. 1) through a link 48 which connects the treadle to a crosshead 50 (Fig. 2) connecting the lower ends of the sliding shafts 28 and rigidly secured thereto. In order that the gages 40 and 42 may be readily retained in their respective work-gaging positions while the work is being arranged for the flange forming operation, a pawl 52 is pivoted between upstanding ears 54 on the treadle 46 and arranged, when in operative position as 30 shown in Fig. 1, to engage the forward face of a horizontal arm 56 connecting the forward legs of the machine frame, the upper extremity of the pawl engaging the lower edge face of an abutment plate 58 secured to the arm 56. The pawl 52 is provided with a tripping tail 60 for use in releasing the pawl.

In order to unite the toe piece and the vamp, the toe piece support 14 is constructed and arranged for movement toward the vamp support 12 in order to cause the vamp engaging flange formed on the toe piece to be brought into engagement with the toe piece engaging flange formed on the vamp. Preferably, a temporary union between the toe piece and the vamp is effected by means of adhesive, for example, latex adhesive or rubber cement applied to the appropriate marginal surface of each of the shoe parts before the parts are mounted upon the illustrated machine. The invention also includes within its scope the provision of a permanent union of the shoe parts by pressing together the juxtaposed marginal flanges. A permanent union may, for example, be effected by applying pyroxylin cement to the appropriate marginal surfaces of the work parts prior to the operation of the present machine and then permitting the cement to dry. An activator, for example, acetone, is applied to one of the cemented surfaces either immediately preceding or immediately after the flange forming operation and the cemented surfaces are held under substantial pressure for a sufficient time to create a permanent bond therebetween. In the illustrated machine, the assembly of the shoe parts is effected by a movement of the toe piece support toward the vamp support and, accordingly, the vamp support 12 is fixed to the table 10 of the machine frame and the toe piece support 14 is secured to a carriage 62 which is herein illustrated as a slide arranged for movement from front to back of the machine. The carriage 62 travels in a substantially T-shaped guideway 64 in the table 10 (Fig. 2) and it is supported upon plates or gibbs 66 secured to the under side of the table and arranged to un-

derlie opposite marginal portions of the under surface of the carriage. In order to move the carriage 62 from its position in Fig. 1 to its position in Fig. 5 and thereby to bring the shoe parts into assembled relation to each other, a rack 68 is arranged to extend downwardly from the under surface of the carriage 62 and a gear 70 is secured to a cross shaft 72 (Fig. 2) and arranged to mesh with said rack. The gear 70 is rotated in a counterclockwise direction as seen in Fig. 1 by depressing a treadle 74 which operates the gear 70 through a series of connections comprising a sprocket wheel 76, a chain 78 cooperating with said sprocket wheel and a rope or wire 80 secured to one end of the chain 78 and extending therefrom forwardly of the machine, over a pulley 82, and then downwardly to the treadle 74. After the cycle of operations is completed, the toe piece support 14 is returned to its initial position by a spring 84 secured to one end of the chain 78 and anchored to the machine frame. The return movement of the toe piece support is limited by the forward end of the carriage 62 engaging an abutment plate 86 (Fig. 2) secured to the machine table and arranged to locate the toe piece support in operative relation to the flange former 22.

The operation of the machine is as follows:— The treadle 46 is partially depressed in order to bring the work gages 40 and 42 into operative position, in which position they are retained by the pawl 52. A vamp 88 is then mounted with its flesh side uppermost upon the vamp support 12 and its inner edge face is brought into engagement with the gage plate 40. A toe piece 90 is mounted with its flesh side uppermost upon the toe piece support 14 and brought into engagement with the gage plate 42. While the shoe parts are manually held upon the work supports, the treadle 46 is further depressed in order to cause the flange formers to engage the appropriate marginal portions of the work and bend them over upon the work supports in order to form marginal flanges therein. While the shoe parts are still held manually against the work supports, the operator releases the pressure on the treadle 46 thereby permitting the return of the flange forming unit to its initial position by the compression springs 34. In this position, as shown in Fig. 5, the flange forming unit is elevated sufficiently to permit the toe piece support 14 to travel rearwardly without obstruction by the work gages. After the release of the flange former unit the operator depresses the treadle 74 in order to bring the toe piece support 14 into its position shown in Fig. 5 wherein the marginal flanges formed in the shoe parts are accurately brought together. The operator then applies to the treadle 74 a sufficiently heavy pressure to create a bond between the marginal flanges of the toe piece and the vamp which have been previously treated with adhesive. The treadle 74 is then permitted to return to its initial position and the united shoe parts are then removed from the machine.

Having described my invention, what I claim as new and desire to secure by Letters Patent of the United States is:

1. In a machine for operating upon sheet material, a work support, a flange former comprising a plate movable perpendicularly relatively to the work support, said plate having a flange forming edge face arranged in parallel relation to a flange forming edge face of the work support and constructed and arranged to co-

operate with the flange forming edge face of said support to form a flange between said edge faces, and a work gage carried by the flange former and having its work gaging edge face arranged in parallel relation to said edge faces of the flange former and the work support.

2. In a machine for operating upon sheet material, a horizontal work support, a flange former movable vertically relatively to the work support, said flange former comprising a head 10 slidably mounted in the machine frame and provided with a flange forming plate having a flange forming edge face arranged in parallel relation to a flange forming edge face of the work support, a work gage comprising a plate disposed 15 in a horizontal plane beneath said flange forming plate and having its work gaging edge face arranged in parallel relation to the operative edge faces of the flange former and the work support, and means for holding the flange former 20 in a position in which the flange forming plate is vertically spaced from the work support while the work gage is in operative position.

3. In a machine for operating upon sheet material, a work support and a flange former relatively movable in order to form a flange in the marginal portion of the work, a work gage carried by the flange former, means for supporting the flange former in an inoperative position, means for moving the flange former toward the work 30 support, and means for positioning the flange former in a position in which said work gage is located in operative relation to the work while said flange former is vertically spaced from the work support.

4. In a machine for operating upon sheet material, a work support and a flange former relatively movable in order to form a flange in the marginal portion of the work, a work gage carried by the flange former, a yielding support 40 for holding the flange former in an inoperative position, a treadle, connections from the treadle to the flange former whereby actuation of the treadle brings the flange former into operative position, and means associated with the treadle 45 for positioning the flange former in a position in which the work gage is in operative position while the flange former is in an inoperative position.

5. In a machine for operating upon the toe 50 piece and the vamp of an imitation moccasin upper, a support for the toe piece, a support for the vamp, a flange former movable relatively to said supports, said flange former comprising a head provided with a flange forming plate con- 55 structed and arranged to operate on the vamp and provided with another flange forming plate constructed and arranged to operate on the tongue, and means for actuating said flange former.

6. In a machine for operating upon the toe piece and the vamp of an imitation moccasin upper, a support for the toe piece, a support for the vamp, a flange former constructed and arranged to cooperate with the toe piece support in 65 order to form in the toe piece a marginal vamp engaging flange, another flange former constructed and arranged to cooperate with the vamp support in order to form on the vamp a marginal toe piece engaging flange, and a car- 70 rier for the flange formers movable perpendicularly relatively to the work supports.

7. In a machine for operating upon the toe piece and the vamp of an imitation moccasin upper, a support for the toe piece, a support for the 75

vamp, a flange former constructed and arranged to cooperate with the toe piece support in order to form in the toe piece a marginal vamp engaging flange, another flange former constructed and arranged to cooperate with the vamp support in order to form on the vamp a marginal toe piece engaging flange, work gages carried by the flange formers, respectively, and a carrier for the flange formers movable perpendicularly relatively to the work support.

8. In a machine for operating upon the toe piece and the vamp of an imitation moccasin upper, a support for the toe piece, a support for the vamp, a flange former constructed and arranged to cooperate with the toe piece support in order to form in the toe piece a marginal vamp engaging flange, another flange former constructed and arranged to cooperate with the vamp support in order to form on the vamp a marginal toe piece engaging flange, and a sliding head constructed and arranged to carry the flange formers.

9. In a machine for operating upon the toe piece and the vamp of an imitation moccasin upper, a support for the toe piece, a support for the vamp, a flange former constructed and arranged to cooperate with the toe piece support in order to form on the toe piece a marginal vamp engaging flange, another flange former constructed and arranged to cooperate with the vamp support in order to form on the vamp a marginal toe piece engaging flange, and a sliding head normally held retracted and constructed and arranged to carry the flange formers.

10. In a machine for assembling the toe piece and the vamp of an imitation moccasin upper, a support for the toe piece, a support for the vamp, a flange former constructed and arranged to cooperate with the toe piece support in order to form on the toe piece a marginal vamp engaging flange, and another flange former constructed and arranged to cooperate with the vamp support in order to form on the vamp a marginal toe piece engaging flange, said toe piece support and said vamp support being relatively movable to bring the toe piece and the vamp into assembled relation and to press said flanged margins together.

11. In a machine for assembling the toe piece and the vamp of an imitation moccasin upper, a support for the toe piece, a support for the vamp having its supporting surface in a plane common to the supporting surface of the toe piece support, a flange former constructed and arranged to cooperate with the toe piece support in order to form on the toe piece a marginal vamp engaging flange, and another flange former constructed and arranged to cooperate with the vamp support in order to form on the vamp a marginal toe piece engaging flange, said toe piece support and said vamp support being constructed and arranged for relative movement in the plane of their supporting surfaces in order to bring said flanged margins together.

12. In a machine for assembling the toe piece and the vamp of an imitation moccasin upper, a support for the vamp, a support for the toe piece constructed and arranged for movement into and from a position in which the toe piece and the vamp are arranged in assembled relation to each other, a flange former constructed and arranged to cooperate with the vamp support in order to form on the vamp a marginal toe piece engaging flange, and another flange former constructed and arranged to cooperate with the toe piece support in order to form on the toe piece a marginal vamp engaging flange, work gages extending downwardly from said flange formers, respectively, and a carrier for said flange formers constructed and arranged to move the flange formers into operative relation to said supports and to return them to a position remote from said supports in order to permit a movement of the toe piece support toward the vamp support whereby the marginal vamp engaging flange formed in the toe piece is brought into engagement with the marginal toe piece engaging flange formed in the vamp.

13. In a machine for assembling the toe piece and the vamp of an imitation moccasin upper, a fixed support for the vamp, a support for the toe piece movable toward and from the vamp support and normally held in a position remote from the vamp support, means for moving the toe piece support into a position in which the toe piece and the vamp are arranged in assembled relation to each other, a flange former constructed and arranged to cooperate with the vamp support in order to form on the vamp a marginal toe piece engaging flange, and another flange former constructed and arranged to cooperate with the toe piece support in order to form on the toe piece a marginal vamp engaging flange.

14. In a machine for assembling the toe piece and the vamp of an imitation moccasin upper, a member constructed and arranged to support a vamp provided with a marginal toe piece engaging flange, and a member constructed and arranged to support a toe piece provided with a marginal vamp engaging flange, said vamp support having an edge face arranged for engagement with said toe piece engaging flange throughout its entire extent, said toe piece support having an edge face arranged for engagement with said vamp engaging flange throughout its entire extent, said supports being relatively movable to bring the toe piece and the vamp into assembled relation and to press said flanged margins together.

15. In a machine for assembling the toe piece and the vamp of an imitation moccasin upper, a fixed member constructed and arranged to support a vamp provided with a marginal toe piece engaging flange, and a member constructed and arranged to support a toe piece provided with a marginal vamp engaging flange, said toe piece support being movable relatively to the vamp support in order to bring said marginal flanges together.

16. In a machine for assembling the toe piece and the vamp of an imitation moccasin upper, a fixed support for the vamp, a support for the toe piece movable toward and from the vamp support, a flange former movable relatively to the vamp support in order to form in the vamp a marginal toe piece engaging flange, another flange former movable relatively to the toe piece support in order to form in the toe piece a marginal vamp engaging flange, work gages extending downwardly from said flange formers, respectively, and a carrier for said flange formers constructed and arranged to move the flange formers into operative relation to said supports and to return them to a position remote from said supports in order to permit a movement of the toe piece support toward the vamp support whereby the marginal vamp engaging flange formed in the toe piece is brought into engagement with the marginal toe piece engaging flange formed in the vamp.

17. In a machine for assembling the toe piece and the vamp of an imitation moccasin upper, a fixed support for the vamp, a support for the toe piece movable toward and from the vamp support, a flange former movable relatively to the vamp support in order to form in the vamp a marginal toe piece engaging flange, another flange former movable relatively to the toe piece support in order to form in the toe piece a marginal vamp engaging flange, work gages extending downwardly from said flange formers, respectively, a carrier for said flange formers nor-

mally arranged to support the flange formers in a position wherein said work gages are located out of the path of movement of the toe piece support, and a latch for holding the carrier in a 5 position wherein said work gages are located in operative relation to the work.

18. In a machine for assembling imitation moccasin vamps and toe pieces, the combination of means for forming a flange on the marginal 10 portion of the vamp adjacent to its concave edge, means for forming a flange on the marginal portion of the toe piece adjacent to its convex edge, means for simultaneously operating said flange

forming means, and means for relatively moving the vamp and toe piece after the flanges are formed to press the flanges together.

19. In a machine for assembling an imitation moccasin vamp with its toe piece, the combination of means for simultaneously forming a flange on the marginal portion of the vamp adjacent to its concave edge and on the marginal portion of the toe piece adjacent to its convex edge, and means for relatively moving the toe 10 piece and vamp to bring said flanges into contact with each other.

HOMER F. SMITH.
